United States Patent Office

Des. 205,980
Patented Oct. 11, 1966

205,980

OVEN

Robert G. Wilson, 643 E. Faris Road, Greenville, S.C.

Filed Dec. 3, 1965, Ser. No. 46

Term of patent 14 years

(Cl. D81—10)

Fig. 1.

Fig. 2.

I claim:

The ornamental design for an oven, substantially as shown.
